UNITED STATES PATENT OFFICE.

STEPHEN LASCO, OF TUNKHANNOCK, PENNSYLVANIA.

GUIDE DEVICE FOR MUSICAL INSTRUMENTS.

Application filed May 12, 1926. Serial No. 108,631.

This invention relates to an attachment for musical instruments and has for its object the provision of a novel guide device adapted to be clamped upon a violin for the purpose of guiding the bow in its movement over the strings so as to enable the user to learn the proper way to bow.

An important and more specific object is the provision of guide means of this character including a pair of devices adapted to be clamped upon the opposite sides of a violin, the devices including upstanding spaced guides between which the bow operates, the guides being separated a slightly greater distance than the bow so as to permit a certain degree of irregularity in the movement such as is bound to occur during normal or natural movements of the player's arm.

Yet another object is to provide a device of this character which will be simple and inexpensive in manufacture, easy to apply or remove, positive in action, efficient and durable in service, and a general improvement in the art.

With the above and other objects and advantages in view, the invention consists in the details of construction and the arrangement of elements to be hereinafter more fully described and claimed, and illustrated in the accompanying drawings, in which:—

Figure 1 is a cross sectional view through a violin with the device applied, the view being taken on the line 1—1 of Figure 2.

Figure 2 is a fragmentary side elevation, and

Figure 3 is a detail sectional view showing the clamping means.

Referring more particularly to the drawings, the letter A designates the body of a violin which is provided with the usual waist portion B which is well known to be considerably narrower than the major width of the body. The instrument of course further includes the usual neck, finger-piece, and other details which are not shown in the drawings, for the reason that they constitute no part of the present invention. The letter C designates the strings which are of course brought across the bridge D in the usual manner. The letter E represents the bow which is used for playing in the well known manner.

In carrying out the invention, I provide guide devices located at opposite sides of the head or body of the instrument, these

guide devices being indicated generally by the numeral 10. Inasmuch as these devices are both identically of the same construction, a description of one will suffice. Each of the members 10 comprises a pair of elongated upright bars 11 connected by transverse elements 12 and 13 engageable upon the top and beneath the bottom of the violin body, respectively, as clearly indicated in the drawings. The securing means is immaterial and may be of any preferred style and it is conceivable that the parts might be formed integral if such should be found preferable for any reason. The members 11 are spaced apart a sufficient distance to permit free operation of the bow E therebetween in the playing of the violin in the usual manner and it is preferable that the confronting faces of the members 11 be provided with linings of felt 14 or the like so as to avoid scratching or otherwise injuring the bow. The member 13 is provided with a lateral extension or is made relatively wide as compared with the member 12 and threaded therethrough are clamping screws 15 which are preferably provided with rubber caps or tips 16 for the purpose of avoiding injury to the instrument.

In order to apply the invention, the two members 10 are disposed at opposite sides of the waist portion B of the violin and the screws 15 are tightened in order to effect a clamping action. Obviously, the member 10 will thus be firmly held with respect to the head or body of the violin so that there will be no danger of displacement of the guide devices when the instrument is bowed in the usual manner. Obviously, there will be the great advantage of preventing inaccurate bowing for the reason that it is impossible to move the bow in any direction other than at right angles to the strings. Of course, there should be a certain play between the sides of the bow and the guides in order to avoid limiting the movement to an unnecessary extent or to an extent which might interfere, to a certain extent at least, with the proper playing of compositions. It is really believed that the construction, operation and advantages will be readily apparent to one skilled in the art without further explanation.

While I have shown and described the preferred embodiment of the invention, it should be understood that I reserve the right to make such changes in the form,

construction and arrangement of parts as will not depart from the spirit of the invention or the scope of the subjoined claim.

Having thus described the invention, I

5 claim:—

A bow guiding means for attachment upon a violin, comprising a pair of similar guide devices disposable at opposite sides of the body of a violin at the waist portion 10 thereof, means for clamping said guide devices in place, each of said guide devices in-

cluding a pair of spaced uprights arranged in parallel relation and connected by transverse elements, one transverse element being disposed upon the top of the body and the other at the bottom thereof, and clamping screws passing through the bottom transverse member and engaging against the underside of the body.

15 In testimony whereof I affix my signature.

STEPHEN LASCO.
